UNITED STATES PATENT OFFICE

CONRAD H. ZIERDT, OF ROSEDALE, PENNSYLVANIA, ASSIGNOR TO THE UNION SWITCH & SIGNAL COMPANY, OF SWISSVALE, PENNSYLVANIA, A CORPORATION OF PENNSYLVANIA

HIGHWAY-CROSSING SIGNAL

Application filed August 22, 1928. Serial No. 301,214.

My invention relates to highway crossing signals, that is, signals located at intersections of railways and highways, for warning users of the highway when a train is approaching the crossing along the railway.

I will describe one form of highway crossing signal embodying my invention, and will then point out the novel features thereof in claims.

10 In the accompanying drawing, Fig. 1 is a top plan view showing the intersection of a highway and a railway provided with a highway crossing signal embodying my invention. Fig. 2 is a sectional view, showing 15 a portion of the apparatus illustrated in Fig. 1, and also embodying my invention.

Similar reference characters refer to similar parts in both views.

Referring to the drawing, the reference 20 characters 1 and 1^a designate the track rails of a stretch of railway track, which rails are supported by the usual cross ties A. This stretch of railway track intersects a highway indicated diagrammatically at H.

25 Located adjacent the crossing of the railway and the highway is a highway crossing signal comprising an electro-responsive sound producing device, here shown as a loud speaker D of the usual and well known form.

30 The loud speaker D is connected with the secondary 6 of a transformer T, the primary 5 of which is constantly supplied with energy from a battery 4 through a device B.

The device B is located in the trackway at 35 a point some distance from the highway H, and as best seen in Fig. 2, is attached to the rail 1^a by means of a bar C, which is secured to the flange of the rail by clamps E and E¹, and bolts F and F¹. The device B is constructed in such manner that, when the device 40 is vibrated, the current supplied to the primary of transformer T is varied in response to the vibrations of the device. In the form here shown, the device B comprises a microphone having an insulating housing J containing two spaced carbon blocks G and G¹.

45 The space between the blocks G and G¹ is filled with loose carbon granules K. The device B is connected in the circuit with the primary 5 of transformer T by means of

wires 2 and 3, which wires are connected with the carbon blocks G and G¹, respectively.

The operation of the apparatus is as follows: When a train, approaching highway H in the direction indicated by the arrow, is 55 passing device B, the vibration of the track rail 1^a caused by the train, is transmitted to device B by means of the bar C, and device B is continuously vibrated until the train has passed beyond device B for some distance. 60

While device B is being vibrated, the carbon granules K within the device are continually agitated, and the resistance of the path between carbon blocks G and G¹ of device B is continuously varying, so that primary 5 of 65 transformer T is supplied with a continuously varying current. This varying current in primary 5 of transformer T induces a varying electromotive force in secondary 6 of transformer T, and the resultant current 70 which then flows in loud speaker D operates the speaker, thereby warning users of the highway of the approach of a train along the railway.

It is a well known fact that a microphone 75 of the type described varies its resistance, and therefore the current in the circuit in which it is connected, in direct proportion to the intensity of the vibrations which are transmitted to the microphone. It is also a 80 well known fact that a loud speaker is capable of converting variations in current into sound waves which correspond to the vibrations which produced the variations in current.

Since loud speaker D is supplied with current 85 which varies in response to the variations in the resistance of device B, and since the resistance of device B is varied in response to vibrations produced by a train in the vicinity of the device, it will be apparent that loud speaker D produces sound waves which are a 90 reproduction of the sound waves caused by the train which is approaching highway H along the railway. It will be plain, therefore, that I have provided a crossing signal which 95 reproduces sound waves created by a train approaching the crossing, and which for this reason is very effective to warn users of the highway of the approach of a train along the 100 railway.

Although I have herein shown and described only one form of crossing signal embodying my invention, it is understood that various changes and modifications may be made therein within the scope of the appended claims without departing from the spirit and scope of my invention.

Having thus described my invention, what I claim is:

10. 1. In combination, a stretch of railway track intersected by a highway, a microphone arranged to be vibrated by a train approaching said highway, and a loud speaker located adjacent the intersection of said highway and said stretch and responsive to vibration of said microphone.
20. 2. In combination, a stretch of railway track intersected by a highway, an electro-responsive sound producing device located adjacent the intersection of said stretch and said highway, and means located in the trackway and responsive to vibrations produced by a train approaching the highway for operating said electro-responsive device.
30. 3. In combination, a stretch of railway track intersected by a highway, an electro-responsive sound producing device located adjacent the intersection of said stretch and said highway, a transformer having its secondary connected with said device, means for supplying the primary of said transformer with current, and means located in the trackway for varying the current supplied to said primary in response to vibrations produced by a train approaching the highway.
40. 4. In combination, a stretch of railway track intersected by a highway, an electro-responsive sound producing device located adjacent the intersection of said highway and said stretch, and means for supplying said device with current which is varied in response to vibration produced by a train approaching the highway.
50. 5. In combination, a stretch of railway track intersected by a highway, a loud speaker located adjacent the intersection of said stretch and said highway, and means located in the trackway and responsive to vibrations produced by a train approaching the highway for operating said loud speaker.
60. 6. In combination, a stretch of railway track intersected by a highway, a microphone located in the trackway at a point some distance from said highway and arranged to be vibrated by a train approaching the highway, a circuit for said microphone, and a loud speaker receiving energy from said circuit and located at the intersection of said highway and said stretch for warning users of the highway of the approach of a train along the railway.
70. 7. In combination, a stretch of railway track intersected by a highway, a loud speaker located adjacent the intersection of said highway and said stretch, a transformer

having its secondary connected with said loud speaker, a microphone located in the trackway and subjected to vibrations produced by a train approaching the highway, and means controlled by said microphone for supplying the primary of said transformer with current.

8. In combination with a stretch of railway track, a loud speaker, a transformer having its secondary connected with said loud speaker, a source of electromotive force, a microphone clamped to a track rail of said stretch, and a circuit for said microphone including said source of electromotive force and the primary of said transformer.

9. In combination with a stretch of railway track, a loud speaker, a device located in the trackway and arranged to vary its electrical resistance in response to vibration produced by a train moving along the trackway, and means for supplying said loud speaker with current which is varied in response to the variation in electrical resistance of said device.

10. In combination with a stretch of railway track, a microphone in the trackway provided with an electrical circuit and arranged to vary the current in said circuit in response to sound waves produced by a train moving along said stretch, and a loud speaker receiving energy from said circuit for faithfully reproducing the sound waves which caused the microphone to vary the current in said circuit.

11. In combination, a stretch of railway track intersected by a highway, a rigid bar, means for clamping said bar transversely to the flange of one rail of said stretch at a point remote from said crossing, an insulating housing attached to said bar, a microphone in said housing, and a loud speaker located adjacent said crossing and controlled by said microphone.

12. In combination, a stretch of railway track intersected by a highway, a microphone attached to a track rail so as to be vibrated by a train approaching the highway, and a signal for said highway controlled by said microphone.

13. In combination, a stretch of railway track intersected by a highway, a highway signal located at said intersection, a microphone attached to a track rail, and means for causing operation of said signal when said microphone is vibrated by a train approaching the highway.

In testimony whereof I affix my signature,
CONRAD H. ZIERDT.
